United States Patent Office

Des. 182,567
Patented Apr. 22, 1958

182,567

REFRIGERATED DISPLAY CASE

Frederick D. Chapman, Chicago, and Kim Yamasaki,
Lombard, Ill., assignors to Hussmann Refrigerator Co.,
St. Louis, Mo., a corporation of Delaware

Application March 12, 1957, Serial No. 45,227

Term of patent 14 years

(Cl. D80—11)

FIG. 1

FIG. 2

Fig. 1 is a perspective view of a refrigerated display case embodying our new design, the rear being substantially plain,

Fig. 2 is a side elevational view of the display case, and
Fig. 3 is a front elevational view of the display case.

The dominant features of our design reside in the full line portions of the drawings.

We claim:

The ornamental design for a refrigerated display case, substantially as shown and described.
